RHEOSTAT

William L. Bliss, Niagara Falls, N. Y., assignor to
 USL Battery Corporation, Niagara Falls, N. Y.,
 a corporation of New York

Application January 21, 1938, Serial No. 186,210

2 Claims. (Cl. 201—48)

This invention relates to rheostats, or variable resistances.

An object of my invention is to provide a rheostat that may be inexpensively constructed.

5 Another object is to provide a means for introducing into a circuit a resistance without an appreciable amount of arcing at the contact points between said circuit and said resistance.

A further object is to provide a simple and 10 effective means for cutting into and cutting out of a circuit a varying amount of resistance wire.

With these and other objects in view, one embodiment of my invention contemplates a flexible resistance element, or a series of such 15 elements, a fixed electrical contact at one end thereof, a second electrical contact member adapted to contact the resistance element at more than one point at any one time, such as a pulley which may be in contact with several 20 turns of a flexible helical resistance element at one time, and means for varying the relative positions of said resistance and said second contact member. By virtue of such an arrangement, under the proper conditions of tension, the flexible 25 resistance will conform itself to the configuration of the second contact member, so that there will be a number of points of mutual contact. In the above-cited instance of a pulley and a helix, if there be several points of contact between 30 the two, that amount of current flowing through any one contact will be considerably less than the total current in the circuit and, as any contact is broken, the amount of arcing which accompanies the break, is very much less 35 than if the total amount of current were interrupted as the contact member moved from one part of the resistance to another. Moreover, there is much less wear in the resistance wire when a rolling contact is employed, rather than 40 a sliding contact.

Other objects, features and advantages of this invention will be apparent from the following description and appended drawings, in which like reference numerals indicate like parts of 45 that embodiment of the invention herein shown and described.

In the accompanying drawings:

Fig. 1 is an elevation of a rheostat comprising the subject matter of this invention.

50 Fig. 2 is an elevation of the same with all the resistance cut out of the circuit.

Fig. 3 is a diagrammatic representation of the electrical circuit involved therein.

Fig. 4 is a detailed view showing the junction 55 of two helices of different diameter.

Fig. 5 is a partial section of Fig. 4.

Fig. 6 shows a flexible conductor by which means one end of the resistance wire is affixed to a support.

Fig. 7 shows means by which the other end of 5 the resistance wire is affixed to its support.

Fig. 8 is a detailed sectional view of a pulley and the resistance helix in contact therewith.

Reference numeral 10 indicates a transverse 10 supporting member from which a vertical member 11 depends, the two members forming a frame in the shape of a T upon which the rheostat may be mounted. The frame may be made of any suitable material; it has been found convenient to employ wood for member 10 and an ordinary 15 electrical conduit of metallic tubing for member 11, in which may be inserted a fuse socket 12, a snap switch 13, and an ammeter 14.

Fastened to member 10 are two hooks, 15 and 20 16, a fuse block 17 and a pulley 18.

The resistance unit consists of a helix 19 of wire of suitable high resistance alloy, such as nichrome, one end of said helix being affixed to a flexible low resistance conductor 20 which in turn hangs from hook 15, and the other end 25 being affixed to a chain 21 depending from hook 16.

From a point intermediate of the ends of horizontal member 10, depends pulley 18 through 30 which helix 19 passes, so that, as shown in Fig. 1, 30 the helix being supported at some point intermediate both ends, it may hang in two loops 23 and 24 in the general form of a W.

Pulleys 25 and 26 ride on the helix at the bottom of each of the loops and are connected to 35 each other by suitable means such as a rope 27, which passes through a pulley 28 extending upwardly from a point near the lower end of vertical member 11. The rope is adjusted so that the helix is under sufficient tension to keep the 40 adjacent turns thereof separated from one another.

As here illustrated, that part of the helix which is more remote from the fixed terminal thereof, or the right hand part of the helix, as viewed in 45 Fig. 1, may be of a lighter, higher resistance wire formed into a helix of somewhat reduced diameter, for the current in the circuit is, of course, much less when most of the resistance is cut in; consequently, the more remote wire is called upon 50 only to handle the lighter currents, and by using a lighter wire, a considerable saving is effected in the cost of manufacturing. The lighter wire 29, and the heavier one 30, may be joined together 55 as shown in Figs. 4 and 5, by making the outside 55

diameter of the helix of the former just enough larger than the inside diameter of the latter that the one may be screwed into the latter, the turns of the helix serving as threads. To prevent excessive bending strains at this junction, it has been found advisable to insert within the smaller helix, a third helix 31 which acts as a reinforcement or stiffener at this point.

Fig. 3 shows the wiring diagram for the rheostat. Numeral 32 indicates the direct current power line to which the rheostat is connected in series with the load. It will be seen that from the positive wire of power line 32, the current flows through one of the two fuses 33 inserted in fuse block 17, through flexible conductor 20 and that part of the resistance helix which hangs in loop 23, through pulley 18, fuse 34 in fuse socket 12, and ammeter 14, to the positive side of the load. From the load it returns to the negative line of the power line, through the other one of the fuses 33. It will be seen from Figs. 1 and 2 that loop 23 may be enlarged or diminished by appropriate manipulation of the rope 21, thereby increasing or lessening the resistance of the circuit. Flexible conductor 20 is of such length that it will extend from hook 15 to pulley 18 when it is desired to eliminate entirely the high resistance helix from the circuit as shown in Fig. 2.

Fig. 6 shows in detail the construction of flexible conductor 20, which is merely a multi-strand copper wire, one end of which is looped over the last turn of the helix 19 and the other end of which is affixed to a clip 35 which may engage hook 15, as well as bind the loose ends of the conductor and furnish means for soldering or otherwise electrically connecting thereto wire 36 leading to the power line.

Rather than connecting the other end of the helix directly to hook 16, in which event that portion of the helix adjacent thereto could never enter into the electrical circuit, it has been found more economical to substitute therefor a short length of chain or other suitable tension member designated by reference numeral 21 and shown in detail in Fig. 7. The chain is fastened to hook 16 by means of an intermediate hook 37 and swivel joint 38 which permits relief from any strains in the helix occasioned by its tendency to unwind or wind.

It will be observed from Fig. 8 that the variable contact between the resistance wire and the load in this rheostat is effected between the helix and the pulley and is of rolling rather than of sliding nature. Moreover, inasmuch as several turns of the helix 19 are in contact with the pulley 18 at any one time during adjustment of the rheo-

stat, only one current path of several in parallel is broken at any instant, and the current in that path being only a fraction of the total, the arcing between and the subsequent corrosion of the contacting members will be greatly reduced.

Although I have shown and described only one embodiment of my invention, it is understood that various additions thereto, modifications thereof, and changes in the shape, size, and arrangement of parts or other details of construction may be made or effected without departing from the spirit of my invention or the scope of the subjoined claims.

I claim:

1. In a device of the class described, a support, a relatively long flexible resistance suspended by its ends from spaced points in said support, said resistance being helical in form and adapted to be longitudinally resilient, a grooved contact member cooperating with the resistance at predetermined points along its length, a flexible cord-like member movable about a point spaced from the contact member and having its ends cooperating with the resistance adjacent the sides of the contact member, said cord-like member under manual manipulation being adapted to change the position of the resistance with relation to the contact member and to maintain the resistance under longitudinal tension so as to bear firmly against the contact member to give a good contractual relation therebetween, and an electrical circuit between one end of the resistance and the contact member.

2. In a device of the class described, an overhead support, an elongated resistance member supported at its ends at spaced points in said overhead support and depending therefrom, an auxiliary supporting member of electrical conducting material secured to said overhead support between said spaced points, over which said elongated resistance passes, whereby said resistance member is caused to assume a double-U configuration, said resistance member being in electrical contact with said auxiliary supporting member, elongated manually operable means positioned in the lower portion of each U of said resistance member and passing around a fixed point spaced downwardly from said resistance member for holding said resistance member in firm contact with said auxiliary support, and an electrical circuit connected to one end of said resistance member and said auxiliary support member whereby the amount of resistance in said circuit may be varied by manipulating said manually operable means to vary the relative lengths of said U-portions of said resistance member.

WILLIAM L. BLISS.
